UNITED STATES PATENT OFFICE.

CHRISTIAN W. HERSHEY, OF READING, PENNSYLVANIA.

FLUE-CLEANING MECHANISM.

1,257,485.

Specification of Letters Patent. Patented Feb. 26, 1918.

Application filed April 19, 1917. Serial No. 163,127.

To all whom it may concern:

Be it known that I, CHRISTIAN W. HERSHEY, a citizen of the United States, residing at Reading, in the county of Berks and 5 State of Pennsylvania, have invented certain new and useful Improvements in Flue-Cleaning Mechanism, of which the following is a specification.

My invention relates to a boiler flue cleaning mechanism and my object is to provide a simple and economic device that will insure the desired results, and may be readily installed and conveniently operated. Other 10 objects will appear in the following specification describing my invention in connection with the accompanying drawings, and the novel features are pointed out in the claims.

Figure 1 is a sectional side elevation of the flue end of a boiler having my cleaning 15 mechanism installed therein in preferred manner.

Fig. 2 is an end view of the same, part of the end wall being broken away to show more clearly the distributing pipe and its 20 return-bend extensions.

Fig. 3 is an enlarged view of a portion of the distributing pipe with its series of controlling valves, one of which is shown in sections.

Fig. 4 is a sectional view taken on the line 4—4 of Fig. 3.

Figs. 5 and 6 are respectively a side and an end view of one of the nozzles employed.

In the drawings 1 represents the fire-box, 25 2 the front wall, 3 the end of the boiler, 4 the boiler flues, and 5 the smoke chamber of a well-known type of boiler construction.

To clean the boiler flues 4, jets of steam are employed, from nozzles located adjacent 40 the ends of the flues and in communication with the steam supply, series of these nozzles being controlled by valves to give intermittent flow, so as to reverse the flow of products of combustion in only a few flues at a 45 time.

My improved device comprises a distributing pipe 10 arranged horizontally adjacent the end of the boiler 3, and spaced therefrom, as shown, by brackets 11. This 50 pipe 10 is connected at one end by pipes 12, 13, 14, 15, and 16 to the main steam supply pipe 17 and its opposite end is closed by a cap 18. Controlling valves may be inserted in the pipes one of which 19 is preferably 55 located, as shown on the outer face of the front wall 2 for convenient operation.

This distributing pipe 10, is preferably made up of aligned sections of pipe having interposed fittings 20, 20, 20. The fittings shown are crosses with their outlets all lying 60 in a plane parallel with the end of the boiler 3. To the bottom outlets 21, 21, 21 are secured extension pipes 22, 22, 22, which are preferably formed of pipe sections of different sizes, as shown, and connected by L's to form section bends of substantially S-shape, the ends of the extensions being closed by caps 23, 23, 23. These extensions depend in front of the flues 4, and are provided with series of nozzles 25, one for each flue 4. 70 Straps 24, 24, 24 from the pipe 10 support the overhanging portions of the extensions 22, 22, 22.

Within each bottom outlet 21, of a fitting 20, as clearly shown in Figs. 3 and 4, is inserted a valve seat ring 30, and the upper outlet 31 is provided with a closure cap 32 forming a bearing for the stem 33 of a valve 34 adapted to seat in said ring 30. Secured to the outlet 31, by the cap 32, is a bracket 80 35 which forms a bearing for a crank shaft 36 arranged parallel with the pipe 10. The crank portions 37, 37, 37, of this shaft 36 are adapted to rotate in cam rings 38, 38, 38, one of which is attached to the outer end of each 85 valve stem 33. To keep the rings 38, 38, 38 in proper alignment at right angles to the cranks 37, 37, 37, the valve stems are prevented from rotating by any well-known means such as making them square as indicated. The cranks 37, 37, 37 are inclined 90 at different angles to the axis of the shaft 36, so that their rotation in the rings 38 will lift one valve at a time as shown.

To one end of the shaft 36 is secured a 95 drive wheel 40, which is connected by drive belts 41, 42, to a crank wheel 43 located adjacent the valve 19 for controlling the supply of steam to the distributing pipe 10.

The nozzles 25 preferably employed in my 100 device are indicated in Figs. 5 and 6, and consist as shown of a tube 25 having a nut portion 50 for screwing it into an extension pipe 22, 22, or 22. The end wall 51 is provided with a central opening 53, and outer 105 inclined-slot apertures 54, 54, so that the steam jet will flow out in two spreading flat sprays that striking the cylindrical walls of the flues 4, will cause them to whirl and advance through the flue in a spiral stream as 110 assisted by the central opening jet.

My distributing pipe and its nozzle exten-

sions is of simple cheap pipe construction, but adequate for the purpose desired and properly located in the smoke chamber adjacent the ends of the flues to be cleaned, 5 while the steam control valve form the main steam supply and the intermittent controlling mechanism for each series of nozzles is conveniently located outside said chamber on the front wall of the boiler for operation 10 when desired. And the reducing pipe extensions and whirling spray nozzles insure an equalized jet force for each flue to be cleaned. If desired additional extensions from the 15 distributing pipe or directly from the steam supply may be provided with nozzles on the top of the boiler for cleaning the upper surface of the latter.

What I claim is:—

1. In a boiler flue cleaning mechanism, a 20 distributing pipe located within the smoke chamber adjacent the end of the boiler and communicating with the steam supply, return-bend extensions of said pipe each having a series of nozzles arranged opposite the 25 ends of the flues to be cleaned, a series of valves in said pipe controlling the flow of steam to the respective extensions, a crank shaft arranged parallel with said pipe and adapted to operate said valves, and means 30 outside the smoke chamber for actuating said crank shaft.
2. In a boiler flue cleaning mechanism, a 35 distributing pipe located within the smoke chamber adjacent the end of the boiler, a steam pipe communicating with said distributing pipe and having a valve outside said smoke chamber, return-bend extensions of said distributing pipe each having a 40 series of nozzles arranged opposite the ends of the flues to be cleaned, a series of valves in said distributing pipe controlling the flow of steam to the respective extensions, a crank shaft arranged parallel with said distribut-

ing pipe and adapted to operate said valves, and a drive belt connected to said crank 45 shaft and extended outside said smoke chamber, and a crank handle for operating said drive belt located adjacent the valve in said steam pipe.

3. In a boiler flue cleaning mechanism a 50 distributing pipe connected to the steam supply and comprising alined pipe sections and interposed cross fittings, a return-bend extension from a vertical outlet of each fitting having a series of nozzles arranged opposite the ends of the flues to be cleaned, a valve seat ring within said vertical outlet, a closure cap for the diametrically opposite outlet forming a valve stem bearing, a 55 stemmed valve in said fitting adapted to seat on said ring and having a cam ring on the stem extension outside said cap, a crank-shaft supported in parallel relation to said distributing pipe and having its crank portions adapted to rotate in said cam rings, 60 and means to rotate said crank shaft.

4. In a boiler flue cleaning mechanism a 65 distributing pipe connected to the steam supply and comprising alined pipe sections and interposed cross fittings, a return-bend extension from a vertical outlet of each fitting having a series of nozzles arranged opposite the ends of the flues to be cleaned, a valve seat ring within said vertical outlet, a closure cap for the diametrically opposite 70 outlet forming a valve stem bearing, a non-rotatable stemmed-valve in said fitting adapted to seat on said ring and having a cam ring on the stem extension outside said cap, a crank-shaft supported in parallel relation to said distributing pipe and having its crank portions adapted to rotate in said cam rings, 75 and means to rotate said crank shaft.

In testimony whereof I affix my signature. 80
CHRISTIAN W. HERSEY.
